UNITED STATES PATENT OFFICE.

ERNEST R. PACKER, OF SIDNAW, MICHIGAN.

RAILROAD-TIE.

1,286,749.

Specification of Letters Patent.

Patented Dec. 3, 1918.

Application filed July 24, 1918. Serial No. 246,568.

To all whom it may concern:

Be it known that I, ERNEST R. PACKER, a citizen of the United States, residing at Sidnaw, in the county of Houghton and State 5 of Michigan, have invented certain new and useful Improvements in Railroad-Ties, of which the following is a specification.

This invention is a railroad tie and has for its principal object the production of a 10 device which will positively hold the rails against spreading when in use without the employment of spikes or like securing means.

Another object of this invention is the production of a railroad tie which consists 15 of a channeled body provided with a top plate together with securing means for the top plate, whereby the rails placed in engagement with the tie will be firmly supported and will be held against any tendency of side displacement.

Another object of this invention is the production of a railroad tie wherein the top plate is provided with supporting blocks at its ends, for relieving part of the supporting strain from the channeled body, while the clips are carried upon the top 25 plate for engaging the rail and holding the same against displacement.

One practical form of construction and 30 assembly of the present invention will be hereinafter described and is illustrated in the accompanying drawing, in which—

Figure 1 is a top plan view of the railroad tie, illustrating the manner in which 35 the rails are connected thereto.

Fig. 2 is a central longitudinal section through the tie, and

Fig. 3 is a transverse section taken on the line 3—3 of Fig. 1.

In the preferred embodiment of the present invention, about to be described, it will be seen that the tie comprises a channeled body which includes a base 5 having parallel side walls 6. This body may be of substantially the same size as the ordinary tie now in use and it is obvious that this body may be made of any desired material, without departing from the spirit of the present invention. By the construction thus disclosed, 45 it will be seen that the body is substantially U-shaped in cross section, as illustrated in Fig. 3.

The top plate 7 is substantially the same length as the body and is narrow to fit between the side walls 6, as shown in the several figures of the drawing. In order

to support this top plate 7 at a distance slightly below the top edges of the top walls, blocks 8 are fixed to the under surface of the top plate 7 and engage the base 5 of the 60 body, thus supporting the plate 7, as illustrated in Figs. 2 and 3. It will be noted that these blocks are carried at the ends of the body and engage the side walls, thus providing a narrow space through the tie 65 which will allow air to freely circulate therethrough and keep the same in a dry condition. It will also be noted that bolts 9 may be passed through the side walls and also through the top plate 7, for holding this 70 top plate against accidental displacement.

The retaining clips 10 are elongated and have gripping flanges 11 upon their inner ends, it being noted that these clips 10 are held in set position upon the top plate 7 75 by the bolts 12 extending through the top plate and also through the clip, as illustrated clearly in Figs. 2 and 3.

An adjustable clip 13 also rests upon the top plate 7 and also has a longitudinal slot 80 14 therein and is provided with a flange 15. This clip 13 is held in an adjusted position by the bolt 16 passing through the top plate 7 and also through the slot 14. Therefore, a rail 17 may be interposed between the fixed 85 and adjustable clips, as illustrated clearly in Fig. 2 it being noted that the base of the rail will fit under the flange 15 and then the flange 15 of the adjustable clip 13 may be slipped over the base of the rail and the 90 bolt 16 adjusted for holding the same in adjusted position. It should be noted that the side walls 6 of the base are provided with alined notches 18 to allow the rails to pass therethrough and also rest upon the top surface of the top plate 7.

When the device is in use, the body is placed upon a road bed and then the top plate, provided with the clips secured as hereinbefore specified is placed upon the 100 body and bolted in engagement therewith to hold the body against displacement. At this time, the rails may be placed upon the tie, by extending through the notches 18 and also resting upon the top surface of the 105 plate 7. The clips will then be engaged with the base of the rails, as hereinbefore specified, thus fixing the rails in set position and preventing accidental spreading of the same when in use. It will be noted that the 110 notches will tend to hold the rails against any tendency of spreading, while the man-

ner in which the clips are engaged with the rail and with the top 7, the manner in which the plate is supported below the top edges of the side walls 6 will hold the rails within 5 the notches and for this reason the rails will be positively held against accidental spreading.

The foregoing description and the drawings have reference to what may be considered the preferred, or approved, form of 10 my invention. It is to be understood that I may make such changes in construction and arrangement and combination of parts, materials, dimensions, et cetera, as may prove 15 expedient and fall within the scope of the appended claims.

Having thus fully described my invention, what I claim as new and desire to secure by Letters Patent, is:—

- 20 1. In a device of the character described, the combination of a body consisting of a base having parallel walls, said walls having notches in their top edges, a plate interposed between said side walls, blocks carried by said plate and engaging said base, thus supporting said plate, means passing through said walls, for holding the plate against accidental shifting, and means carried by said plate for engaging rails for holding the same within said notches, thus holding the same against spreading.
- 25 2. In a device of the character described, the combination of a body consisting of a base having parallel walls, said walls having notches in their top edges, a plate interposed between said side walls, blocks carried by said plate and engaging said base, thus supporting said plate, means passing through said walls for holding the plate against accidental shifting, and rail engaging means carried by said plate.
- 30 35

Copies of this patent may be obtained for five cents each, by addressing the "Commissioner of Patents, Washington, D. C."

by said plate and engaging said base, thus supporting said plate, and means carried by said plate for engaging rails, for holding the same within said notches, thus holding 40 the rails against spreading.

3. In a device of the character described, the combination of a body consisting of a base having parallel walls, said walls having notches in their top edges, a plate interposed between said walls, blocks carried by 45 said plates and engaging said base thus supporting the said plate adjacent the top edges of said walls, the upper surface of said plate being in alignment with the surface of said 50 notches, means passing through said plate for holding the same against accidental shifting and means carried by said plate for engaging rails for holding the same within said notches, thus holding the rails 55 against spreading.

4. In a device of the character described, the combination of a body consisting of a base having parallel walls, a plate interposed between said walls, blocks carried by 60 said plate and engaging said base, thus supporting said plate, means passing through said walls for holding the plate against accidental shifting, and rail engaging means carried by said plate.

In testimony whereof I affix my signature in presence of two witnesses.

ERNEST R. PACKER.
